(57) **CLAIM**

The ornamental design for a golf tee, as shown and described.

DESCRIPTION

FIG. 1 is a perspective view of a golf tee showing our design;

FIG. 2 is a front elevation view thereof;

FIG. 3 is a right side elevation view thereof;

FIG. 4 is a top plan view thereof;

FIG. 5 is a left side elevation view thereof;

FIG. 6 is a rear elevation view thereof; and,

FIG. 7 is a bottom plan view thereof.

The broken line shown in FIG. 4 is included for the purpose of illustrating a portion of the golf tee that forms no part of the claimed design.
